UNITED STATES PATENT OFFICE.

ELDOR M. ELLIASON, OF DONALDSON, MINNESOTA.

ATTACHMENT FOR HARVESTERS AND BINDERS.

1,199,678.

Specification of Letters Patent. Patented Sept. 26, 1916.

Application filed June 16, 1916. Serial No. 104,019.

To all whom it may concern:

Be it known that I, ELDOR M. ELLIASON, a citizen of the United States, residing at Donaldson, in the county of Kittson and State of Minnesota, have invented new and useful Improvements in Attachments for Harvesters and Binders, of which the following is a specification.

This invention relates to attachments for harvesters and binders, and it has for its object to produce a simple and improved device which may be easily applied to any harvester or binder of conventional construction and which will operate to save grain by facilitating the passage of short grain over the sickle bar and to the platform apron without necessity of lowering the reel to an excessive extent where it will be in danger of breaking.

20 A further object of the invention is to produce a simple and improved attachment which will facilitate the passage of grain and especially of short grain upon the platform apron to the elevator and which will 25 keep the grain straight and in good condition for binding.

A further object of the invention is to produce a simple and improved device of the type described which may be readily 30 fitted to harvesters and binders of various types and makes.

With these and other ends in view which will readily appear as the nature of the invention is better understood, the same consists in the improved construction and novel arrangement and combination of parts which will be hereinafter fully described and particularly pointed out in the claims.

In the accompanying drawing has been 40 illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a top plan view showing a portion of a binder to which the invention has been applied. Fig. 2 is 50 a bottom plan view showing the improved device detached from the binder. Fig. 3 is a sectional detail view taken on the line 3—3 in Fig. 1. Fig. 4 is a sectional detail view taken on the line 4—4 in Fig. 1.

55 Corresponding parts in the several fig-

ures are denoted by like characters of reference.

The top and bottom members 15, 16 of the improved device consist of plates of suitable material, such as galvanized sheet 60 metal, each plate being of a length substantially equal to the length of the platform of the machine in connection with which it is to be used. The top and bottom plates are relatively narrow although the 65 top plate is of a width materially exceeding the width of the bottom plate. The top and bottom plates are provided at their front edges with hinge lugs 17, 18 engaging a rod or pintle 19 whereby the parts are 70 hingedly connected. The top and bottom plates are connected together by screws 20 about which springs 21 have been coiled for the purpose of spacing the top and bottom plates apart. The bottom plate is provided 75 with transverse grooves or corrugations 22, and it has a plurality of apertures 23. Connected adjustably with the top plate 15 adjacent to one end thereof is a tongue 24 having slots 25 engaged by the attaching 80 bolts 26, said tongue extending upwardly with respect to the top plate.

In practice the improved attachment is 85 connected with the finger bar S of a harvester or binder, the grooves or corrugations 22 serving to accommodate the bolt heads or nuts of the fastening members whereby the guard fingers are secured. The device is attached by means of short screws 27 engaging the finger bar through the apertures 23, and said screws being obviously short so that they will not obstruct the movement of the sickle bar. The top plate 15 will overhang the front bar F of the platform frame, and it will also overhang the front edge of 90 the platform apron A, the springs 21 serving to sustain the top plate 15 in spaced position above the platform apron. The tongue 24 will extend across the gap between the platform apron and the elevator E. 95 The device will thus constitute a guide whereby the grain will be conveyed over the finger bar to the platform apron, greatly facilitating the passage of short grain and avoiding loss thereof. The device will also prevent the narrow interspace between the finger bar and the platform apron from becoming choked or obstructed by short grain lodging therein.

105 The improved device, as will be seen is 110

extremely simple in construction and is capable of being manufactured and installed at a very moderate expense. It has proven in actual practice to be thoroughly efficient 5 for the purpose for which it is intended.

Having thus described the invention, what is claimed as new, is:—

1. An attachment for harvesters and binders comprising a narrow plate of a 10 length substantially equal to the length of the finger bar, means whereby said plate may be mounted on the finger bar, a second plate hingedly connected with the first plate at the front edge thereof and overhanging 15 the rear edge thereof sufficiently to extend over the finger bar and over the front edge of the platform apron, and means for connecting and resiliently spacing said plates to the rearward of their hingedly connected 20 front edges, thereby sustaining the rearward portion of the top plate above the front portion of the platform apron.
2. In an attachment for harvesters and binders, a bottom plate, means whereby said 25 plate may be mounted on a finger bar, a top plate hingedly connected with the bottom plate at the front edge thereof, connecting members extending through the two plates, and springs coiled about said connecting 30 members.

3. An attachment for harvesters and

binders comprising a bottom plate, means for securing said plate on a finger bar, a top plate hingedly connected with the bottom plate at the front edge thereof, said top 35 plate extending rearwardly above the front edge of the platform apron, connecting members extending through the two plates, and springs coiled about said connecting members, the top plate having a tongue adjustably connected therewith adjacent to one end thereof.

4. An attachment for harvesters and binders comprising a corrugated bottom plate, a top plate hingedly connected with 45 the bottom plate at the front edge thereof, said top plate being of a width materially exceeding the width of the bottom plate, means whereby the bottom plate is connected with a finger bar, the corrugations of 50 the bottom plate serving to accommodate portions of the fastening means whereby the guard fingers are secured on the finger bar, connecting members extending through the top and bottom plates, spacing springs 55 coiled about said connecting members, and a tongue adjustably connected with the overhanging portion of the top plate adjacent to one edge thereof.

In testimony whereof I affix my signature. 60

ELDOR M. ELLIASON.
